UNITED STATES PATENT OFFICE.

JOHN M. SHIMER, OF WILKINSBURG, PENNSYLVANIA, ASSIGNOR TO WILSON-SNYDER MANUFACTURING COMPANY, A CORPORATION OF PENNSYLVANIA.

PUMP.

Application filed December 16, 1927. Serial No. 240,448.

This invention relates to pumps and more particularly to hot oil pumps such as are employed in oil refining and oil cracking plants.

5 A pump used in pumping hot oil at a temperature of from 600° to 800° F. is subject to considerable expansion and, with ordinary pump constructions, this expansion causes misalignment of the cylinder bore with the power end, and also misalignment 10 of the tie rod bearings with the tie rods associated therewith. Such misalignment is, of course, a very undesirable operating condition.

15 An object of this invention is to provide a pump of the type set forth, so constructed and arranged that expansion or contraction of the pump block will have no effect on the alignment of the cylinder bore or other

20 parts.

A further object is to provide a hot oil pump having an improved pump or cylinder block supporting mechanism.

25 A still further object is to provide an arrangement of the type set forth which will be simple in construction, effective in operation and relatively cheap to manufacture and assemble.

These and other objects which will be apparent to those skilled in this particular art 30 are accomplished by means of the invention illustrated in the accompanying drawings, in which Figure 1 is a view in side elevation of the liquid end of a hot oil pump constructed in accordance with one embodiment 35 of this invention, and Fig. 2 is an end elevation taken from the right of Fig. 1 with certain parts broken away and shown in section.

40 In the particular embodiment of this invention which has been chosen for illustration, a cylinder block 5 of standard construction is associated with two oppositely disposed reciprocating plungers 6 and 7, respectively, which are provided with the usual reciprocating cross heads 8 and 9 connected by tie rods 10 and 11 extending longitudinally along each side of the cylinder block, so that the respective plungers may be simultaneously operated by a single piston rod 12 driven from any desired source of power (not shown).

45 It will be readily apparent that supporting the cylinder block directly upon a foot or foundation, as has usually been done,

will result in a substantial misplacement of the cylinder bore center, when the pump is in operation and pumping oil at high temperature. The extreme temperature of the liquid results in such an expansion of the 60 pump block as to cause a lifting of the cylinder bore vertically and consequently shifting such bore out of alignment with the power end. When the tie rod bearings are supported, as is usual, directly upon the cylinder block, it will be apparent that the lateral expansion of such block will result 65 in the outward movement of the bearings relatively to the tie rods with the result that the latter are more or less bowed and 70 bind in such bearings.

In order to overcome the disadvantages inherent in the standard method of supporting pumps when such pumps are subjected to any considerable amount of expansion or 75 contraction, I provide supports for the pump of such construction as to permit free and practically unlimited expansion and contraction thereof without causing any misplacement of the parts. As illustrated, the cylinder 80 block 5 is supported at the side so as not to directly engage the foundation itself, instead of resting upon an ordinary foot or other standard form of foundation. The supporting structure engages the cylinder 85 block at points near the vertical center thereof. A foundation 13 is provided with supporting castings 14 on each side thereof spaced from the cylinder block. Each casting has a tie rod bearing 15 through which 90 the associated tie rod extends, and each bearing is rigidly secured to the supporting foundation in any desired manner. Shims 16 are preferably positioned under each casting 95 so as to permit accurate adjustment and leveling of each casting on its support. The top of each casting is provided with a flat face on which a block supporting bracket 17 is slidably mounted and each bracket is rigidly secured to the adjacent face of the cylinder block 5 in any desired manner. Preferably, each bracket may be provided with a lug 18 seated in a lug receiving bore 19 provided in the face of the block. It will be observed, therefore, that it 100 is important that the lateral projections or brackets 17 shall provide at both sides of the block horizontal, downwardly-facing flat shoulders which rest and slide on horizontal, upwardly-facing flat faces formed on the 110

foundation members 14. It will be observed also that it is important that, in addition to suspending the cylinder block slidably on the upwardly-facing horizontal faces of the 5 foundation members, there shall be provided a clearance all around the cylinder block, so that the body of the cylinder block shall be free to expand in all directions without interference by any part of the foundation, to 10 the end that alignment of the plungers and the cylinder-bore shall be always maintained irrespective of expansion and contraction of the cylinder block.

If mechanical power is employed, the supporting brackets will be secured to the cylinder block above the horizontal plane of the center of the cylinder bore. In this way the expansion of the supports for the block 20 upwardly under the influence of the hot oil is counteracted by the expansion of the block downwardly from the point of support, with the result that the location of the center line 25 of the cylinder bore remains constant. If steam power is employed, the supporting brackets will be connected to the cylinder block at points nearer to such plane. It will be apparent that this manner of mounting the cylinder block permits free expansion 30 thereof around the center of the cylinder bores in all directions with the result that the plunger bore remains in alignment with the power end of the installation. Supporting the tie rod bearings in a separate casting which is not directly connected to the block 35 in any manner permits the tie rod bearings to keep their original position in spite of any expansion or contraction of the associated cylinder block.

What I claim as new and desire to secure 40 by Letters Patent is:

1. The combination in a pump having a cylinder block, of oppositely disposed reciprocating plungers, a cross head associated with each of said plungers, tie rods connecting said cross heads and bearings for said tie rods independent of the cylinder block.

2. The combination in a hot oil pump having a cylinder block, of oppositely disposed reciprocating plungers, a cross head associated with each of said plungers, tie rods connecting said cross heads and means for supporting the cylinder block so as to permit movement thereof independent of said bearings.

3. The combination in a hot oil pump having a cylinder block, of a supporting foundation provided with elevated supporting shoulders on each side of said block, supporting castings mounted on each shoulder 60 and provided with tie rod bearings and

block supporting castings secured to the side faces of said block and slidably mounted upon said first castings so as to permit free expansion of said block independent of its support.

4. The combination with a pump block having a cylinder bore of a supporting foundation spaced from said block and means for mounting said pump block on said foundation so that the center line of said cylinder bore is substantially stationary irrespective of expansion or contraction of said block or foundation.

5. The combination in a hot oil pump, of a cylinder block provided at opposite sides 75 with projecting members having their under faces flat and horizontal, and a foundation for supporting said cylinder block, said foundation having supporting members at each side of said cylinder block provided 80 with horizontal upwardly-facing flat faces on which slidably rest the downwardly-facing flat faces of the cylinder block, said cylinder block at a point below the said flat supporting faces being narrower than the 85 foundation members and the bottom of the cylinder block being unsupported by the foundation, whereby the cylinder block will be free to expand in all directions with reference to the supporting members while 90 maintaining the center line of the bore of the cylinder substantially constant with respect to the center line of the plungers working therein.

6. In a hot oil pump, the combination of 95 a foundation having at opposite sides upwardly-extending members each of which is provided with a horizontal upwardly-facing flat surface and also with a bearing for a tie-rod, a cylinder block suspended between 100 said upwardly-extending foundation members and having at its opposite sides projecting members provided with flat downwardly-facing shoulders resting on said upwardly-facing surfaces of the foundation 105 members, there being a clearance between the foundation and the cylinder block to permit the cylinder block to expand in all directions without interference by the foundation, plungers working in the opposite ends of the bore in said cylinder block, a cross-head connected to each of said plungers, and a tie-rod connecting the ends 110 of said cross-heads and resting in the tie-rod bearings aforesaid, for the purposes herein 115 set forth.

In testimony whereof, I have hereunto subscribed my name this 13th day of December, 1927.

JOHN M. SHIMER.
